UNITED STATES PATENT OFFICE

BENJAMIN TALBOT, OF PENCOYD, PENNSYLVANIA.

METALLURGICAL FURNACE.

SPECIFICATION forming part of Letters Patent No. 571,250, dated November 10, 1896.

Application filed April 14, 1896. Serial No. 587,453. (No model.)

To all whom it may concern:

Be it known that I, BENJAMIN TALBOT, a subject of the Queen of Great Britain and Ireland, and a resident of Pencoyd, Montgomery county, Pennsylvania, have invented certain Improvements in Metallurgical Furnaces, of which the following is a specification.

My invention consists of certain improvements in continuous heating-furnaces, the usual construction of such furnaces being such that the material to be heated is introduced at or near one end of the furnace and removed at or near the other end, the products of combustion entering the furnace at that end from which the charge is removed and escaping from the furnace at the charging end.

One object of my invention is to so combine regenerators with such a continuous furnace that the air may be properly heated for admixture with the incoming gases, and a further object is to provide the furnace with a more durable bottom or bed than that usually employed. These objects I attain in the manner hereinafter set forth, reference being had to the accompanying drawings, in which—

Figure 1 is a longitudinal section of a heating-furnace constructed in accordance with my invention. Fig. 2 is a transverse section 30 of the same, on an enlarged scale, on the line 2 2, Fig. 1. Fig. 3 is a similarly-enlarged transverse section on the line 3 3, Fig. 1; and Fig. 4 is a transverse section on the line 4 4, Fig. 1.

The furnace itself may be constructed in any ordinary manner, that shown in the drawings consisting of a structure A, partly inclined and partly straight, the forward or charging end being highest, and having a 40 doorway a, which when uncovered permits of the introduction of the ingots, bars, or other forms of metal to be heated, the charge being forced along on the bed of the furnace as each new addition is made thereto, and the 45 heated bars, ingots, or other objects being finally withdrawn through any desired number of lateral delivery-openings b, appropriately located near the rear end of the furnace.

At its rear end the furnace communicates, 50 through an opening d and a flue d', with a gas-producer B of any desired character, and also through openings f with a transverse cham-

ber f', which is in communication, through short necks g², with the rear ends of longitudinal flues g g' beneath the furnace, these 55 flues being in communication at their forward ends with chambers D D', respectively, and these chambers containing the usual brick checkerwork or other heat absorbing and distributing structures. 60

The chambers D D' communicate, respectively, at their rear ends with flues F F' beneath the same, and each of said flues F F' communicates at its forward end through a neck h with a casing G, containing a valve i, 65 by the adjustment of which the flue F may be placed in communication with the air and the flue F' with a discharge-flue H, leading to the stack, as shown in Fig. 4, or vice versa.

The products of combustion escape from 70 the forward end of the heating-chamber of the furnace through side flues m, which unite in a transverse flue n beneath the forward end of the furnace, said flue n communicating through necks p p' with the forward ends 75 of the regenerating-chambers D D'. The flow through each of the necks g², p, and p' is controlled by a valve s, of any desired character, the preferable form of valve being a sliding water-cooled valve having a water-cooled 80 seat. Instead of using an independent valve for each neck I may use a single valve, such, for instance, as the valve i, (shown in Fig. 4,) for controlling the flow through both necks. It will be seen that by proper adjustment of 85 these valves and of the valve i in the casing G the products of combustion from the furnace on their way to the stack may be caused to pass rearwardly through either of the regenerating-chambers D D', while at the same 90 time air is passing forwardly through the other regenerating-chamber, and thence through one of the flues g or g', one of the necks g², the chamber f', and openings f for admixture with the gases entering the fur- 95 nace from the producer, the valves being so manipulated that the regenerators are used alternately as absorbers and distributers of heat.

A partition I, of fire-brick, tile, or other refractory material, forms part of the bottom of each flue g g' and extends so far forward that the air is compelled to traverse each regenerative chamber D or D' to the forward end of 100

the same before it can enter the flue g or g' , thereby providing for the effective heating of said air before its admixture with the gases.

Sight-holes t are formed in the sides of the 5 furnace at intervals, so that the contents of the heating-chamber may be readily inspected.

I provide the heating-chamber of the furnace with a composite bed or bottom, that 10 is to say, that portion x of the bed or bottom of the furnace at and near the delivery end of the same is of ordinary basic or neutral lining material, while that portion x' of the bed or bottom of the furnace in the forward 15 portion of the latter is of any ordinary acid lining material.

The provision of the furnace with a bed or bottom of basic material throughout is inadvisable, because the heat of the furnace at 20 the forward or charging end is not usually sufficient to properly form a bottom of basic material, (by forming being meant the setting, hardening, or glazing of the basic material,) while, on the other hand, the use of an acid 25 bottom throughout is inadvisable because of the fluxing of the same by combination with oxid of iron from the metal charge when subjected to high heat such as prevails at that end of the furnace where the gases enter 30 the same. By making the bed or bottom of the furnace partly acid and partly basic or neutral, however, I overcome both of the objections noted.

Although I have shown the regenerators as

being located beneath the furnace, and al- 35 though such location is preferable, it is not essential to the proper carrying out of my invention.

Having thus described my invention, I claim and desire to secure by Letters Patent— 40

1. The combination of a regenerative furnace having inlets and outlets so disposed that the heating-gases always pass through it in the same direction, a gas-generator in communication with the inlet end of the furnace, a pair of regenerators, a pair of valved regenerator-outlets, in communication with the inlet end of the furnace, lateral outlets at the discharge end of the furnace, a transverse chamber beneath the end of the furnace 45 and in communication with said lateral outlets, and valved necks between said chamber and the regenerators, substantially as specified.

2. A metallurgical furnace having a bed or 50 bottom composed partly of basic or neutral material and partly of acid material, the basic or neutral material being disposed at and near that end of the furnace where the heating-gases enter the same, substantially as 55 specified.

In testimony whereof I have signed my name to this specification in the presence of two subscribing witnesses.

BENJAMIN TALBOT.
